UNITED STATES PATENT OFFICE

HENRY MANKEL, JR., OF MCKEAN, PENNSYLVANIA.

VEHICLE RUNNING-GEAR.

SPECIFICATION forming part of Letters Patent No. 308,972, dated December 9, 1884.

Application filed January 24, 1884. (No model.)

To all whom it may concern:

Be it known that I, HENRY MANKEL, Jr., a citizen of the United States, residing at Mc- 5
Keen, in the county of Erie and State of Penn-
sylvania, have invented certain new and use-
ful Improvements in the Running-Gear of
Wagons and Carriages; and I do hereby de-
clare the following to be a full, clear, and exact
description of the invention, such as will en-
able others skilled in the art to which it ap-
pertains to make and use the same.

This invention consists in providing certain
new and useful improvements in the construc-
tion of the running-gears of wagons and car-
riages, as shall hereinafter fully appear.

The invention has for its object economy
in the construction, lightness with additional
strength, and beauty of design.

The invention relates particularly to the
construction of the reach and the fifth-wheel,
the other parts of the gear being made as com-
monly.

The invention is illustrated in the accom-
panying drawings, as follows:

25 Figure 1 is a top plan view of the reach,
fifth-wheel, and fragments of the axles. Fig.
2 is a side view of a part of the reach and all
of the fifth-wheel. Fig. 3 is a bottom plan of
the reach and the upper part of the fifth-wheel.

30 A A' are the axles. B B is the reach. C
is the bolster. D is the lower part of the fifth-
wheel. E is a brace from the lower end of the
king-bolt to the upper part of the fifth-wheel,
and is so formed as to form a guide for the
lower part of said wheel. F is the king-bolt.
G G' are the reach-iron and upper part of the
fifth-wheel, as will be explained fully herein-
after. b, b', and b² are cap-irons on the upper
side of the reach.

40 The essential features of the invention are
the formation of the reach of two pieces
crossed in the form of an X, and making its
main iron a part of the fifth-wheel.

In the drawings, G represents the upper
45 part of the fifth-wheel and the reach-iron back
to the crossing of the two parts of the reach, and
G' represents the balance of the reach-iron.

B' represents the point of crossing of the
reach.

50 I am aware that it is common to construct
a running-gear with a reach consisting of two
bars, which connect with the bolster on each

side of the king-bolt and extend to the hind
axle, near the wheels. These double reaches
have also been connected with the upper part
of the fifth-wheel, as in Patent No. 127,093,
dated May 21, 1872. I am also aware that two
reaches have been bent or curved so as to
come in contact at a point back of the bolster,
and have been ironed by a solid bifurcated
iron, as is shown in Letters Patent No. 118,115,
dated August 15, 1871; but I am not aware
that the two reaches have ever been crossed
in the manner of an X.

Fig. 3 shows the under side of the reach and
the upper part of the fifth-wheel, and it will
there be seen that the reach-irons and the up-
per part of the fifth-wheel are welded together
and form one piece of metal. I expect to
construct this iron as follows: An X-iron will
be struck up in proper form to fit at the
intersecting-point B' of the reaches. The up-
per part of the fifth-wheel will be forged as
commonly, only its rear part will not be curved
to conform to the lower half of the said wheel,
but will be pointed back in proper line to
meet the X-iron, to which the points or ends
will be welded. The parts G' G' of the reach-
iron will be forged as commonly, and welded
to the back prongs of the X-iron. In order
to secure great strength at the intersection, I
expect to make the X-iron of the best ma-
terial, such as Norway iron or steel, and it
may be formed with side lips or flanges to lie
upon the sides of the wood; or it may be made,
as shown, with a slight enlargement at the
crossing-point for bolts g' g' to pass down by
the sides of the reach. A capping X-iron, b,
will also be used, which will be forged or
struck up, as desired. The wooden bars form-
ing the reaches will be halved together at the
point B'.

The wooden bars may be set into the bolster
by tenon and mortise, if desired; but I do
not deem it necessary to do so, as the cap-irons
b' b', which also pass over the bolster, and the
bolts, as shown, form a very strong connec-
tion. By crossing the reaches, as shown, a
much stronger reach is formed than can be
done when the bars are not so crossed, or when
a single center reach is used, unless much
more iron is used in their construction than is
necessary in the construction I show.

The advantage of a crossed reach over a

single center reach or a double-bar reach is that it acts as a truss against lateral strain so perfectly that it requires less bracing, and so saves in cost of material, and is lighter. It 5 also affords better connection with the bolster or head-block, for it can be connected therewith without mortising said block, as I have shown.

I expect that the iron G, which, as above 10 stated, constitutes the upper fifth-wheel iron and the lower **X**-iron of the reach, will be manufactured and sold as an article of commerce, leaving the wagon or carriage maker to supply the other irons from his own forges. 15 The lower fifth-wheel iron, D, may, and very likely would, also be made to accompany the above-named iron G. The iron G, when so made as an article of trade, would end sufficiently back of the point B' to afford opportunity for welding the irons G' thereto. 20

What I claim as new is as follows:

1. In the running-gear of a wagon or car-

riage, the combination, with a reach formed of two crossed bars, of an **X**-iron facing the lower side of said reach, which is projected, substantially as shown, to form the upper part 25 of the fifth-wheel, and a second **X**-iron for facing the top side of said reach, which is projected, substantially as shown, to form a connection with the bolster, said two **X**-irons 30 being connected together by bolts at the intersecting-point of said reach.

2. In the running-gear of a wagon or carriage, the combination of the crossed reaches B B, the combined reach-iron and upper part 35 of fifth-wheel G G', lower fifth-wheel iron, D, and braces E, as shown.

In testimony whereof I affix my signature in presence of two witnesses.

HENRY MANKEI, JR.
